SEWING MACHINE

George Sauer, Berwyn, Ill., assignor to Union Special Machine Company, Chicago, Ill., a corporation of Illinois

Application January 17, 1946, Serial No. 641,681

5 Claims. (Cl. 112—256)

1

This invention relates to improvements in lubricating systems for sewing machines and has reference more particularly to such lubricating systems in which the oil is constantly circulated.

The system of the present invention is especially useful in connection with high speed industrial sewing machines in which constant bathing of moving parts with lubricating oil is desirable or essential for efficient performance.

Prior to the present invention, certain lubricating systems for sewing machines have suffered from the disadvantage that the pump which circulates the oil would at times run dry of oil, with resulting damage to the mechanism. One of the aims of the present invention is to prevent the supply of oil to the circulating pump, also referred to as the first pump, from becoming exhausted, thereby securing more dependable lubrication. A feature in this connection is that the rate of supply of oil to the circulating pump is substantially independent of the speed of the machine and also of the length of the seam-forming operation.

A feature of the invention is that in order to insure effective lubrication, oil is supplied to the lubricated parts at a rate in excess of that which is normally necessary. This oil passes out of the circulating system and passes by the lubricated surfaces, draining therefrom. An aim of the present invention is to provide means for returning this excess oil to the circulating system, thus preventing it from being permanently lost. This means may, for example, comprise a second pump. A special feature of this invention is that the supply of oil to the first or circulating pump is substantially independent, for a considerable period of time, of the transmission of oil through the second pump.

In accomplishing the above objectives, an upper oil reservoir of considerable capacity is provided. Oil is fed by gravity from this reservoir through a conduit to a smaller bore or well. Oil is drawn from this well by the circulating pump and is transmitted to the lubricated parts by means to be described in detail hereinafter. The circulating pump transmits oil at a greater rate than is necessary for lubrication. A considerable part of the oil transmitted by this pump does not pass out of the circulating system to the lubricated parts, but continues in a closed cycle past ports of ducts which lead to those parts, and is returned directly to the well which feeds the circulating pump. In this way, even if the circulating pump transmits oil at a greatly excessive rate, this well will not run dry because such excess oil is again

2

immediately available in the well. Part of the oil transmitted by the circulating pump does pass through ducts to the lubricated parts. Of this latter amount, a certain quantity is in excess of that actually needed for lubrication, and this excess passes by the bearing surfaces and is collected in a lower reservoir. From the lower reservoir it is periodically transmitted by the second pump to the upper reservoir, from which it is returned to the circulating system through the conduit leading to the well, by gravity.

Other objects, features and advantages of the invention will appear from a detailed description of an illustrative form of the same, which will now be given in conjunction with the accompanying drawings, in which:

Fig. 1 is a view in side elevation with parts broken away, of an overedge sewing machine embodying the present improvements.

Fig. 2 is a view of the same machine from the opposite side, partly in elevation and partly in longitudinal section.

Fig. 3 is a detail view of a tubular connecting rod employed in the machine, a portion being broken away to show the construction more clearly.

Fig. 4 is a fragmentary detail view in longitudinal section showing the oil filtering unit.

Fig. 5 is an enlarged fragmentary detail view in vertical section showing the construction of the second pump.

Fig. 6 is an enlarged cross-sectional view showing the first or circulating pump construction.

Fig. 7 is an end elevation view of one of the eccentrics employed in the illustrative construction.

Fig. 8 is a longitudinal section of such an eccentric, and

Fig. 9 is a view, partly in front elevation and partly in section, of the machine with a modified form of lower oil reservoir and filter means installed.

Fig. 10 is a detail view, chiefly in elevation and partly in section, showing a portion of the mechanism for actuating the work advancing means, as seen from the same direction as in Fig. 2.

For purposes of illustration, the invention has been shown applied to an overedge stitching machine of the general type disclosed in the Christensen and Zeier Patent No. 1,751,508, granted on March 25, 1930.

Reference is made to Figs. 1 and 2. Briefly described, the machine includes a base 10 mounted on a plate 11, the plate being supported from a sewing table 12 by insulators or vibration ab-

sorbers 13. Rising from the base is a standard 14 with spaced front and rear projections 15 and 16, respectively, and with inset bearing bushings 17 and 18 for a shaft 19 which is inclined somewhat to the horizontal, and to which, at the left hand or rear end, as shown in Fig. 2, is secured a combined hand and belt wheel 20 so that the machine can be operated either manually or through a belt, driven by appropriate means. Confined to substantially vertical reciprocation in a bushing 21 set into a forwardly reaching projection 22 of the standard is a needle bar 23 which, at its lower end, carries a needle 24, the latter cooperating with a spreader 25 and a looper 26. Mounted on shaft 19 are various rotary actuators or eccentrics, to be mentioned in detail below. Shaft 19, by means of these eccentrics and suitable means, drives the spreader 25 and looper 26 and a work-advancing feed dog (not shown) attached to a feed dog shank 27. For more details of such suitable means, reference is made to Patent 1,864,391, issued to Frederick F. Zeier on June 21, 1932.

Reference is made to Figs. 2 and 10. Cooperating with an eccentric 28 on shaft 19 is an eccentric strap 29, to which is attached a tubular connecting rod 30 at one end of said rod. This rod is terminated at its other or lower end in a split strap 31. This strap forms a socket for a ball stud 32 rigidly clamped to a slotted arm 33 which is pivoted on an axis through 34. The point on arm 33 at which the ball stud is clamped is adjustable so as to vary the angle through which this arm oscillates for a given rotation of eccentric 28. It will later be seen that this will determine the amplitude of the feed stroke and hence the length of the stitch. Rigidly attached to arm 33 by means of an upstanding member 33a is an arm 35. The member 33a may be integral with the member 33, and may comprise a rocker, adapted to pivot about the axis through 34. The arm 35 extends upwardly at an angle to the arm 33, but is in a different plane therefrom; as shown in Fig. 10. The arm 35 is pivotally connected to one end of a link 36 at 36a, the point of connection being adjustable along arm 35. Link 36 is pivotally connected at its other end to a rod 37 which carries the feed dog shank 27, to which a feed dog (not shown) is attached. The rod 37 is carried by a yoke 37a and is mounted for longitudinal reciprocation therein. The rotation of eccentric 28, by means of the linkages described, causes rod 37 to reciprocate longitudinally and thereby imparts back and forth movements to this feed dog. The yoke 37a is pivotally mounted on the member 33a at an axis indicated at 37b, to permit a feed lift motion, to be described at a later point. On the end of the aforementioned ball stud 32 is a projection 38. Screwed to an upper portion of the split strap 31, which is carried by the lower end of the connecting rod 30, is a forked arm 39 which straddles this projection 38 and this prevents the socket of the split strap 31 from unduly wobbling on its ball stud. As shown in Fig. 10, the relation of the rod 30 and its split strap 31 to the ball stud 32 is generally similar to that of the rod 47 and the strap 48 to the ball stud 49, to be mentioned at a subsequent point.

The machine is provided with a trimmer 39a pivoted to a portion of the frame at its left-hand end, of the same general type as that disclosed in the above-mentioned Christensen and Zeier Patent 1,751,508.

The eccentric 40 mounted on shaft 19, co-

operates with a strap 41 which is attached to a tubular connecting rod 42. This connecting rod terminates at its lower end in a split strap 43 which engages a ball stud (not shown) rigidly attached to the trimmer 39a, said ball stud having a projection 43a which is pivotally engaged by an arm 44 at one end of said arm. This arm, at its other end, pivotally engages a projection 37c on the yoke 37a which carries the rod 37, and thereby indirectly engages the rod 37 on which the feed dog shank 27 is mounted. In order to provide a differential feeding motion there may be carried by the yoke 37a another feed dog, not shown. The rotation of eccentric 40 imparts a feed lift, or up and down, motion indirectly to the feed dog carried by the feed dog shank 27 by lifting and lowering the yoke 37a, and also imparts a feed lift motion in a more direct manner to the feed dog carried by this yoke itself. This last-mentioned feed dog will receive a back-and-forth movement as a result of the motion imparted to the yoke 37a by the rocking of the member 33a. The back-and-forth movements of the feed dogs will not be the same, and there will consequently result a differential feeding motion. The advantages of a differential feeding motion are well-known and are pointed out in the above-mentioned Zeier Patent 1,864,391.

Eccentric 45 cooperates with a strap 46 attached to a tubular connecting rod 47, terminating at its lower end in a split strap 48, which engages a ball stud 49. This ball stud is connected by a series of suitable linkages to spreader 25. As a result the rotation of eccentric 45 drives spreader 25.

Eccentric 50 on shaft 19 cooperates with a strap 51 which is connected to one end of a tubular connecting rod 52. At the other end, this connecting rod terminates in a split strap (not shown) which engages a ball stud (also not shown) connected by a series of suitable linkages to looper 26. As a result, the rotation of eccentric 50 drives looper 26.

The details referred to above form no part of the present invention, being included for the sake of a more complete explanation as to an appropriate setting for the invention.

Turning now to provisions for lubrication, reference may be made again to Fig. 1 and Fig. 2. The lubricating system includes a lower oil reservoir or receptacle 53. As shown in Fig. 2, this reservoir is suspended beneath the table. This reservoir has a restricted neck (not shown) and is gripped at this neck by a bottle clamp spring 54, said spring also engaging a circumferentially-slotted cylindrical support 55 in the region of circumferential slots therein (not shown). Support 55 in turn is permanently fastened to the table 12.

The spring is bowed in a substantially circular shape, its respective end portions overlapping and terminating in grips 56 and 57. The inherent spring action is such as to tend to decrease the perimeter of the circle so formed, thus causing the overlap of the end portions to be greater, and causing terminating grips 56 and 57 to be separated by a greater distance. The tendency of the spring to contract results in its gripping the lower reservoir 53. The operator may squeeze grips 56 and 57 together, this movement being in opposition to the inherent spring action of the spring, thereby enlarging the circular opening of the spring, allowing the lower reservoir 53 to be readily removed or attached.

Inside the lower reservoir 53 is an oil filter unit 58. An illustrative embodiment of such an oil

filter unit is shown in Fig. 4. It includes a cylindrical outer cup 59, having a longitudinal axial bore 60. This bore is terminated at its upper end by end wall 61 of the cup, said wall having an opening 62 smaller than said bore, through which opening a tube 63 extends. The lower end of said cup 59 is tapped within said bore 60 to receive a threaded plug 64, which plug itself includes a longitudinal axial bore 65. Tube 63 begins at the lower end of plug 64, extends axially through the bore 65, the larger bore 60, and the opening 62, and upwardly beyond to a pump, as will be hereinafter described.

Plug 64 has a tapped radial opening into which a setscrew 66 is screwed for the purpose of clamping the cup assembly in position on the tube 63. Inserted in the lower end of tube 63 is a plug 67 to seal the end of this tube against passage of oil therethrough, and also to prevent said tube from collapsing under the pressure of said clamp screw.

A cylindrical filter 68 of screen or other suitable filter material is inserted between tube 63 and cup 59, in the bore 60, said filter material fitting snugly against the inner surface of said bore 60 and extending axially from the upper end of plug 64 to the end wall 61 of the cup. A coil spring 69 is inserted between filter material 68 and the tube 63 in order to hold said filter material in position snugly against the inner surface of cup 59.

Cup 59 has at least one, and preferably several, radial ports 70-70, which register with some portion of the filter material. Similarly, tube 63 has at least one, and preferably several, ports 71 which open into bore 60 at some point above the plug 64. It will later be seen that a pump periodically creates a partial vacuum within tube 63, and it can be seen that oil from lower reservoir 53 will then be drawn in through ports 70, through filter material 68, into bore 60 and through ports 71 into tube 63, and upwardly through said tube, being filtered in the process, as desired.

Tube 63 extends upwardly from the aforesaid oil filter, and through this tube oil is drawn by a second pump, mentioned generally heretofore, as 72 in Fig. 1. This pump is actuated by appropriate linkages operated manually, or otherwise by the operator. In the illustrated embodiment, the piston 73 of the pump is actuated by the longitudinal reciprocation of a piston rod 74. This rod passes through an opening 75 in wall 75a, which extends part way across the base. Said rod 74 is connected by a link 76 to an arm 77, said arm being rigidly attached to and preferably integral with a rock shaft 78. Shaft 78 is journaled in a cover plate 79 forming part of the standard 14. Extending radially from shaft 78 is another arm 80 which is clamped to said shaft 78 by a split sleeve 81 and a clamp screw 82.

As shown in Fig. 1, shaft 78 is urged in a counterclockwise direction by spring means 83, one end of which spring means is attached to the cover plate 79 for the standard 14 and the other end of which engages arm 80 and is bent around the same, as shown. The free end of arm 80 is attached to one end of a chain 84 connected at its opposite end to a treadle (not shown). The machine may be conveniently arranged so that the same treadle which actuates arm 80 through chain 84 also actuates a presser foot lift lever 85 through a chain 86. Since the operator operates the treadle in order to raise the presser foot in the normal course of each seam-forming

operation, and since arm 80 is actuated by the same treadle, the piston 73 of the pump 72 will be reciprocated by such action, combined with the restoring action of the spring 83 upon the formation of each seam. In lieu of connecting the arm 80 with the presser foot lifting treadle, it may be connected with a treadle which controls the clutch of the conventional electric transmitter used for driving the machine. This treadle, also, is operated upon each seaming operation. It is of course possible to operate the treadle for the primary purpose of operating the pump 72, and as will later be explained, this will preferably be done prior to starting the machine. This may be done even if the arm 80 is connected with the clutch control treadle, by having more play in the connections to the clutch than to the arm or by operating the treadle for this purpose before the motor is started.

Details of the lift pump are shown in longitudinal section in Fig. 5. The reciprocating action of rod 74, just described, causes piston 73 to reciprocate in a cylinder 86a. Said cylinder is, as shown, fitted into a wall 86b of the standard 14. Tube 63 is connected, as shown, with one end of a bore 87 within the aforementioned wall of standard 14, said bore 87 communicating at its other end with the interior of cylinder 86a. During the suction strokes of the piston 73, oil is drawn up through tube 63, past an intake check valve 88 within said bore, said oil being drawn into cylinder 86a; and during the pressure strokes of said piston 73, the oil is forced through a port 89 at the end of the cylinder, past a discharge check valve 90 and upwards through a tube 91. In Fig. 1 the wall of this tube is partly broken away to show its longitudinal structure.

Reference is again made to Figs. 1 and 2. Extending upwardly from the pump, tube 91 connects with an upper oil reservoir 92 through a port 93. The upper reservoir is, in the embodiment shown, formed as an integral part of a cover 94 at the top of the frame. As an initial condition to operation of the system, this upper reservoir should be supplied with oil by the operator, by operation of the pump means, as described. A portion of the tube 91 may be of transparent plastic, so that the operator can observe the flow of oil through the tube into the upper reservoir, thus being assured that the pump is operating satisfactorily. A transparent L-shaped fitting may be provided for this purpose at the upper end of the tube 91. A sight gauge, not shown, may be provided on the side of the upper reservoir so that the operator can observe the height to which this reservoir is filled with oil.

Reference is again made to Fig. 2 and Fig. 6. Extending from the bottom of the reservoir 92 within the standard 14 is a gravity flow tube or duct 94a which connects with a vertical bore or well 95 in the partition 96, said well 95 being in line with a port 97 in the top of the bearing 18. In the plane of the port 97 the shaft 19 is provided with a groove 99 which extends most of the way but not completely around the shaft within the confines of the bearing 18, and which, it will be noted, is of uniform width and depth throughout its length. At one end, the groove 99 communicates, by way of a radial port 100, with an axial bore or duct 101 in the shaft 19. As shown in Fig. 2, the duct 101 is closed at its front end by a screw plug 102 which is accessible upon removal of a front cover 103. From the duct 101 oil is conducted, by way of one or more radial

ducts 104 in the shaft 19 at each of eccentrics 28, 40, 45 and 50, respectively, to a circumferential groove 105 internally of each eccentric, and from said groove by way of one or more connecting radial ducts 106 in each eccentric to the bearing surface of said eccentrics, the first mentioned ducts 104 containing flow-restricting filter packing as conventionally indicated in Fig. 2.

Figs. 7 and 8 show details of an eccentric or rotary actuator. Bores 106a provide dynamic balancing.

Fig. 3 shows a tubular connecting rod in longitudinal section. Each rod is provided with a longitudinal duct 107. Periodically during the rotation of shaft 19, as shown in Fig. 2, radial ducts 106 register with longitudinal ducts 107 of such tubular connecting rods, and oil thus passes down such rods, thereby being transmitted to bearing surfaces at the opposite end of ducts 107 which require lubrication, such as the ball studs and sockets mentioned previously. In each connecting rod, there is a vent 108, sloping upwardly, connecting the axial duct with the exterior of the connecting rod. Since air can enter this vent, oil in the axial duct is prevented from becoming air-locked.

Within the confines of the bearing 17, the shaft 19 has a radial port 109 which extends from the duct 101 and communicates with a circumferential groove 110 internally of said bearing. Leading upwardly in the bearing 17 from the groove 110 is a port 111 which registers with a vertical bore 112 in a rear wall 113 of the standard 14. At the region of its overlap upon the wall 113, the cover 94 is recessed as at 114 to form in conjunction with an interposed plate 115, a channel or pocket which communicates by way of a port 116 in said plate with the top of the bore in said wall. Extending up from the channel 114 is a tube 117. Part of the wall of this tube is shown broken away in Fig. 2 to show its construction. This tube connects, as shown, with the well 95 through a small cylinder 95a which forms an upward extension of the well. The cylinder 95a may be of transparent plastic so that the flow of oil can be observed therethrough. It is preferably provided at its upper end with an oil cup 118 to permit the introduction of oil from a can whenever desired.

During each rotation of the shaft 19, which is in the direction of the arrow in Fig. 6, a quantity of oil gravitates from the reservoir by way of the connection 94a, the well 95 and the port 97 in the bearing 18, into the interrupted groove 99 in said shaft while the groove is in registry with said port. As the shaft 19 continues in its rotation, the charge of oil which is thus trapped, due to its inertia, cannot follow the rapid movement of the shaft, and part of it is accordingly forced from the groove 99 through the port 100 into the shaft duct 101. Groove 99 is constantly supplied with oil through the port 97 and this is continuously fed into the shaft duct 101 and aided by gravitation, due to the downward slope of the shaft, it is constantly advanced leftward in Fig. 2. The quantity over and above that required to keep the packing in the radial ducts moist is forced upwardly through the port 111 in the bearing 17, the duct 112, port 116, channel 114 and tube 117, and finally is discharged from the top end of the latter into well 95.

For the sake of distinguishing between the pumps, the pump illustrated in Fig. 5 is, as men-

tioned, called the second pump, and the pump formed by groove 99 in shaft 19 is called the first or circulating pump.

A certain amount of oil will escape past the bearing surfaces of the eccentrics, as well as past the piston 13 of the second pump and will drip from other moving parts, and provision is made for catching this oil on a drainage surface 119 of the base 10. Oil drains from this and other surfaces internal of the standard into a sump 120 through a filter 121 (see Fig. 5) which extends across said pump, through appropriate connections with tube 122, and down said tube into the lower reservoir 53. Oil which drains into the lower receptacle is not lost to the circulating system, since it will be pumped into the upper reservoir by the action of the second pump 12 whenever such pump is actuated. Since, as stated, the second pump is actuated by the operator in the normal course of sewing a garment whenever she actuates the presser foot lift lever or shifts the transmitter clutch by means of one of the treadles, oil from the lower reservoir 53 is pumped into the upper reservoir 92 periodically during normal operation of the machine, being filtered in the process. Accordingly, oil replenishment is necessary only at very protracted periods.

It is an important feature of the invention that oil passing through the circulating pump in excess of the amount passing through ports 104 is returned directly to the upper well. In order to assure a supply of oil through duct 101 adequate for lubrication, the circulating pump is designed to transmit oil at a rate always in excess of that required for such lubrication. It is to be observed that tube 94a will present a certain amount of resistance to the replenishment of oil in well 95 from reservoir 92, which reservoir has a considerable capacity. In practice it has been found that even when tube 94a is made of maximum diameter it cannot keep the well 95 supplied with lubricant throughout the formation of a long seam, particularly at high speed. The present invention, however, makes certain that even if the machine operates at high speed, and if the circulating pump transmits oil at a high rate, there is no danger of well 95 running dry of oil. This is because, in the present system, the flow of oil through tube 94a under the force of gravity is not relied upon as part of the closed circulation cycle; on the contrary, when the circulating pump is transmitting oil at a high rate, well 95 relies for replenishment of oil primarily upon the flow of oil through tube 117, which represents the excess oil pumped under pressure through duct 101.

It is to be observed that the lower reservoir 53 and the second pump are not part of the cycle which constantly circulates oil. The purpose of the second pump is merely to return to the circulating system, through the upper reservoir, oil which has drained past the lubricated parts. Accordingly, the supply of oil to the circulating pump is substantially independent of the action of the second pump.

Fig. 9 shows a modified embodiment of the lower oil reservoir or receptacle and associated filter means shown in Figs. 1 and 2. The embodiment of the reservoir and filter means shown in Fig. 9 will later be described in specific terms but it may be generally described as being in the approximate form of a vertical cylinder divided transversely into upper and lower part-cylinders 75 or bulbs, each bulb having a circumferential side

wall and an end wall integral therewith which closes said bulb at one end, the bulbs being fitted one to the other at their other ends by means of a circumferential lip on the side wall of the lower bulb which fits over the side wall of the upper bulb, the interior volumes of the upper and lower bulbs being separated one from the other by a transverse disc-like filter means engaged and supported around its periphery by the side walls of the bulbs in the region where they are fitted together, each bulb being provided in its interior with a generally axial post or column integral with the end wall thereof, the two posts providing additional support for the filter means and being associated with means for providing support for the lower bulb and means for drawing oil from the interior of said lower bulb.

In more specific terms, the oil reservoir and filter means shown in Fig. 9 may be described as follows:

The reservoir comprises upper and lower transparent plastic bulbs, 123 and 124, respectively, each in the general shape of a cup, or a part-cylinder, the axes of the bulbs being generally vertical and in alignment.

The upper bulb 123 is open at its lower end, and the lower bulb 124 is open at its upper end. The upper bulb 123 has a circumferential side wall 125 and an upper end wall 126 integral therewith. Similarly, the lower bulb 124 has a circumferential side wall 127 and a lower end wall 128 integral with said side wall 127. The side wall 127 of the lower bulb has, throughout most of its longitudinal extent, approximately the same diameter as has the side wall of the upper bulb, being in vertical alignment therewith, but said side wall 127 of the lower bulb is provided in the region of its upper edge with a circumferential shoulder 129 and a circumferential lip 130 supported thereon of diameter slightly larger than that of the upper bulb and major portion of the lower bulb, said lip fitting snugly on the outside of wall 125 at the lower edge of said wall.

A disc-like filter 131 comprising an upper layer 132 and a lower layer 133 of filter screen material and an interlayer 134 of filter felt interposed therebetween, generally horizontally disposed, is supported under its outer edge by shoulder 129 and it fits at its periphery against lip 130. When the reservoir is in use, the lip of the lower bulb is fitted over the lower edge of side wall 125 of the upper bulb, which edge is then in contact with the upper surface of filter 131 around the outer edge of said filter.

Integrally attached to the upper inside surface of end wall 128 of the lower bulb 124 is a generally axial cylindrical central post or column 135 extending longitudinally inside said bulb, terminating in the plane of the shoulder 129, contacting the lower surface of the filter 131, and providing additional support therefor.

Similarly integrally attached to the lower inside surface of end wall 126 of the upper bulb 123 is a generally axial cylindrical central post or column 136 extending longitudinally inside said bulb, terminating at the plane in which the lower edge of wall 125 lies, and contacting the upper surface of the filter 131. Posts 135 and 136 may conveniently be of approximately the same diameter, and may be generally in vertical alignment. A bore 137 extends from the lower surface of end wall 128 upwardly through this wall, lengthwise through the post 135, through the filter 131, and lengthwise into post 136. A thumb screw 138 comprising a head 139, a shaft 140 in-

tegrally joined thereto at its one end and threaded at its other end and a cylindrical flange or shoulder 141 at the junction of said head and said shaft, is provided, and the shaft 140 extends upwardly into bore 137 from beneath wall 128. Post 136 is tapped within bore 137 toward its upper end to receive the threaded shaft 140 of thumb screw 138. Wall 128 is provided with a shoulder 142 on its lower surface around the opening of bore 137. When thumb screw 138 is tightened manually, flange 141 engages shoulder 142 and thereby presses the lower bulb upwardly into closer engagement with the upper bulb, and thus causes the filter 131 to be snugly gripped both toward the center between posts 135 and 136 and toward its outer edge between shoulder 129 and the lower edge of wall 125.

It can thus be seen that the filter divides the interior of the reservoir into two sections or receptacles, an upper receptacle 143, and a lower receptacle 144. The upper end wall 126 of the upper bulb is reinforced by being made thicker in one region 126a, and the drainage tube 122 previously mentioned earlier in this application communicates with receptacle 143 through this region. It is recalled that this drainage tube 122 mentioned, in connection with the embodiment shown in Figs. 1 and 2, delivers drainage oil from drainage surfaces within the machine.

Post 135 is provided with a generally axial, horizontal bore 145 extending from receptacle 144 into said post, terminating before reaching bore 137. Wall 126 and post 136 are provided with a reinforced region 136a generally above bore 145, and said wall and said post are provided with a bore 146 extending from the upper surface of said wall downwardly, said bore 146 being tapped to receive a threaded connection 147. Extending from the lower end of bore 146 lengthwise downwardly through post 136, through filter 131, into post 135 and communicating with bore 145 is a bore 148. Leading upwardly from connection 147 is the tube 63 mentioned earlier in this application, which communicates with the pump 72, not shown in this figure. This tube and this pump were mentioned in connection with the embodiment shown in Figs. 1 and 2.

When the reservoir and filter means above described are used in actual operation, oil draining from moving parts of the machine drains through tube 122 into the upper receptacle 143. Oil from this receptacle drains by gravity through the filter into the lower receptacle 144, being filtered in the process. By the pumping action of pump 72, oil is drawn from the lower receptacle through bore 145, upwardly through bore 148, and through tube 63 to the pump 72. The pump when it is operating, lowers the pressure in the lower receptacle 144 as compared with the pressure in the upper receptacle 143, and the drainage of oil from the upper receptacle into the lower receptacle is aided by this pressure difference.

While illustrative forms of the invention have been described in considerable detail, it will be understood that numerous changes may be made in the construction and arrangement of the various parts without departing from the general principles and scope of the invention. The terms and expressions employed herein have been used as terms of description and not of limitation.

I claim:

1. In a sewing machine having bearings, a lubricating system, said system comprising a plurality of separate, intercommunicating upper oil

reservoirs, a first rotary oil-transmitting pump beneath a first of said reservoirs, means comprising a port at the bottom of said first reservoir opening directly into said pump for delivering oil from said first reservoir to said pump, means for leading directly to said first reservoir part of the oil transmitted by said pump, means for delivering to said bearings another part of the oil transmitted by said pump, and means for returning to at least one of said upper reservoirs oil draining from said bearings, said last-mentioned means including an intermittently-acting piston-type pump.

2. In a sewing machine having bearings, a lubricating system, said system comprising an upper oil reservoir, an oil-holding well extending alongside said reservoir but separate therefrom, a gravity conduit connecting an outlet point in the lower portion of said reservoir to a first inlet point of said well, a continuously-acting, rotary, oil-transmitting pump immediately beneath said well, means comprising a port at the bottom of said well opening directly into said pump and forming an intake therefor, an outlet conduit leading from said pump, ducts branching from said conduit for delivering oil to said bearings, a conduit out of direct communication with said reservoir leading from said outlet conduit at a point beyond said ducts to a second inlet point of said well above the surface of oil in said well for returning directly to said well excess oil transmitted by said pump, a lower oil reservoir at an elevation below said bearings for collecting oil draining from said bearings, and an intermittently-acting pump responsive to some intermittent sewing operation for delivering oil from said lower reservoir to said upper reservoir.

3. In a sewing machine having bearings, a lubricating system, said system comprising means forming a first loop-like lubricant path including a pump adapted to circulate oil continuously around said path while said machine is operating, and means including a portion of said first lubricant path forming a second loop-like lubricant path, said second lubricant path including, in addition to said portion common with said first lubricant path, an upper oil reservoir, a gravity conduit from said reservoir to a point of said first lubricant path near the entrance to said pump, means for conducting oil to said bearings from a point of said first path subsequent to said pump, a lower oil reservoir for collecting drainage oil, and an intermittently-acting pump for returning drainage oil from said lower reservoir to said upper reservoir.

4. In a sewing machine having bearings, a

lubricating system, said system comprising means forming a loop-like lubricant path having portions at different elevations, a continuously-acting pump in said path for pumping lubricant around said path, means forming a lubricant path from a point of said loop-like path to said bearings, a collector reservoir at an elevation below said bearings, means forming an oil drainage path from said bearings to said collector reservoir, filter means forming a base for said collector reservoir, a lower storage reservoir beneath said filter means for receiving filtered drainage oil, an upper oil reservoir out of series with said loop-like path lying above said pump and below the uppermost portion of said loop-like path, a conduit leading from said upper reservoir to a point of said loop-like lubricant path near the entrance to said continuously-acting pump, and an intermittently-acting pump responsive to an intermittent sewing operation adopted to deliver oil from said lower storage reservoir to said upper reservoir.

5. In a sewing machine having a frame, a rotary shaft, and at least one actuator mounted on said shaft, said actuator having bearing surfaces, a lubricating system, said system comprising an oil reservoir, an oil-holding well in said frame separate from said reservoir, a conduit leading from an outlet point in the lower portion of said reservoir to a first inlet point of said well, a continuously-acting, rotary, oil-transmitting pump, an intake duct for said pump communicating with a point in the lower portion of said well, an outlet duct for said pump comprising a bore extending longitudinally of said shaft, branch ducts leading from said bore to said bearing surfaces of said actuator, and a return conduit leading from a point of said bore beyond said branch ducts directly to a second inlet point of said well, whereby excess oil transmitted by said pump is returned directly to said well.

GEORGE SAUER.
